UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

SELECTIVE-CURRENT PRODUCTION AND AMPLIFICATION.

Application filed September 23, 1919. Serial No. 325,730.

To all whom it may concern:

- Be it known that I, RALPH V. L. HARTLEY, a citizen of the United States, residing at East Orange, in the county of Essex, State 5 of New Jersey, have invented certain new and useful Improvements in Selective-Current Production and Amplification, of which the following is a full, clear, concise, and exact description.
- 10 This invention relates to the production and control of alternating currents of different frequencies. More particularly it relates to the generation of harmonics from a given base-frequency current and to the control of such generation. The invention relates also to the reinforcement of alternating currents apart from their generation, whether or not the alternating currents stand in harmonic relation to one another.
- 15 20 An object of the invention is to provide a method of and means for regenerating or reamplifying the harmonics being produced, or the alternating currents present, in desired kinds and amounts. A further object 25 is to enable the suppression of any undesired harmonics or other currents so that they do not appear in the work circuits.

According to the embodiment of the invention to be described more in detail hereinafter, a thermionic relay which is overloaded by base-frequency current of sine wave to produce harmonics by distorting the wave, also serves to re-amplify the harmonics that have been produced. Each of 30 the selecting circuits for deriving the harmonics from the output of the distorting relay has a coupling back to the input side of the relay so that current of each frequency is reinforced due to the amplifying 35 property of the relay. By reversing the coupling of any feed-back, the corresponding harmonic may be suppressed. If the source of overloading current is omitted, the same 40 circuit arrangement may be used to amplify separately a number of currents of different 45 frequencies.

In the drawing, diagrammatic circuit arrangements are indicated, of which Fig. 1 50 represents a harmonic producer according to the invention and Fig. 2 represents means for selectively amplifying currents of several frequencies by means of one amplifier.

Referring first to Fig. 1, a repeating ele-

ment 1 has an input or control circuit and an output or work circuit and possesses the property of producing a wave in the output circuit which varies synchronously with the input or control wave but which, for large input energy, is dissimilar to the input wave. That is, the operating characteristic of the repeating element is not linear throughout the operating range used. A repeating element known to exhibit this property, under suitable conditions, is an electron discharge device such as is illustrated, which may comprise an evacuated chamber in which are the usual source of electrons or cathode in the form of the heated filament 2, the anode 3 and the grid or impedance-controlling element 4. The input circuit is fed by alternating current preferably of sine wave and of base frequency, from the generator 5 through the coupling 6. The generator 5 which may be of any suitable type overloads the discharge device 1 so that the repeated wave is distorted and may be regarded as resolvable into a series of sine waves of the original base frequency and the harmonics of that frequency. The repeated wave is transmitted through the coupling 7 to the plurality of parallel circuits 8, 9, 10, 11, etc., tuned, respectively, to the base frequency and to the successive harmonics which are present in the output wave. Coupled to these tuned circuits are the respective work circuits F, H₁, H₂, H₃, etc., each of which contains elements for tuning to the frequency that it is intended to receive.

Heretofore, in harmonic generators of the type thus far described, it has been found that the output of certain of the harmonics, generally the higher frequency ones, is very small and it is desirable that production of such harmonics be increased. In other cases it may be desirable to suppress some harmonics altogether or, at least, not to increase their production. The invention provides means for accomplishing any of these results, as will now be described.

Each work circuit H₁, H₂, etc., into which the harmonics are separately fed, is associated through the respective coupling 12, 13, 14 to the input side of the repeating element 1. The energy so fed back is preferably not sufficient to cause oscillation of the discharge device but permits amplification

of the currents so fed back. Each coupling 12, 13, 14 is independently variable and may be adjusted to feed back no energy or a desired amount of energy to control the degree 5 of amplification. In case it is desired to suppress the production of any harmonic, the corresponding coupling 12, 13 or 14 may be reversed so that the current fed back causes the production of the undesired harmonic to 10 be neutralized. In addition, a shunt path 15 may be provided across some or all the feedback circuits, consisting of adjustable inductance, adjustable resistance, and adjustable capacity whereby any phase adjustment 15 of the current being fed back can be made, as desired.

Other means of accomplishing the same result as that obtained by reducing the degree of coupling 12, 13 or 14 to zero or by 20 reversing the coupling will be obvious to anyone skilled in the art, but the means shown is preferred.

Referring now to Fig. 2, 16 may be a line carrying a plurality of alternating currents 25 of different frequencies which are to be delivered separately to the load circuits L_1 , L_2 , L_3 , etc., which are tuned respectively to the frequencies they are to carry and are coupled respectively to the tuned parallel 30 branches 17, 18, 19, etc., bridged across the line 16. An amplifier 20 of any suitable type amplifies the currents in all or any of the load circuits L_1 , L_2 , L_3 , etc., and impresses them in amplified form through 35 the output coupling 21 upon the line 16. For determining which frequencies are to be amplified and which are to be suppressed and for controlling the degree of such amplification or suppression, the adjustable 40 couplings 22, 23 and 24 are provided between the respective load circuits L_1 , L_2 , L_3 , etc., and the input side of the amplifier 20. In the case of the arrangement of Fig. 2, 45 amplifier 20 is not overloaded by base-frequency current but it carries only the currents that are fed back through the couplings 22, 23, 24, etc. Phase-adjusting circuits 15 are omitted in Fig. 2 but it would be obvious to supply them if desired.

50 While the repeating or distorting or amplifying element has been shown as of the thermionic type, it is to be understood that the invention is not to be limited to the specific form illustrated nor to the circuit 55 arrangement as a whole, nor to the particular details, but only by the scope of the appended claims.

What is claimed is:

1. In the system of harmonic production 60 in which an electron discharge amplifying device is overloaded to produce a distorted output wave from which the harmonics are selected, the method of controlling the amplitude of the produced harmonics which comprises individually feeding back the

energy of a plurality of desired harmonics to the input side of said amplifying device to the exclusion of undesired harmonics.

2. In the system of harmonic production 70 in which an electron discharge amplifying device is overloaded to produce a distorted output wave from which the harmonics are selected, the method of controlling the amplitude of the produced harmonics which comprises feeding back the energy of a plurality of desired harmonics to the input side of said amplifying device and adjusting the 75 phase of the currents so fed back.

3. In the system of harmonic production 80 in which a repeating element is overloaded to produce a distorted wave from which the harmonics are selected, the method of controlling said production of harmonics which comprises feeding back to the input side of 85 said repeating element the energy of two of said harmonics and adjusting differently the respective phases of the currents so fed back.

4. In the system of harmonic production 90 in which a repeating element is overloaded to produce a distorted wave from which the harmonics are selected, the method of controlling said production of harmonics which comprises feeding back to the input side of 95 said repeating element the energy of two of said harmonics and adjusting the phase relations of the respective energies so fed back to cause an increase in the production of one harmonic and a decrease in the production of another harmonic.

5. In a system employing a plurality of 100 circuits each for transmitting current of a different frequency, the method of controlling the energy in all of said circuits comprising impressing individually the current from each circuit upon a common amplifier, amplifying the current in said amplifier, and selectively transmitting the output currents 105 from said amplifier to the several circuits.

6. In a system employing a plurality of 110 circuits each for transmitting current of a different frequency, the method of controlling the energy in all of said circuits comprising impressing the current from the several circuits upon a common amplifier, adjusting individually the amount and the 115 phase relations of the currents so impressed from the several circuits, and selectively transmitting the output currents from said amplifier to the several circuits.

7. A harmonic producer having an output 120 circuit and a control circuit, a plurality of selective paths in said output circuit, and an individual coupling between each said selective path and said control circuit.

8. A harmonic producer having an output 125 circuit and a control circuit, a plurality of selective paths in said output circuit, a coupling between each said selective path and said control circuit, and means for adjusting the phase relation of said couplings. 130

9. A harmonic producer having an output circuit and a control circuit, a plurality of selective circuits coupled to said output circuit, and individual couplings between said selective circuits and said control circuit. 5
10. A source of current waves, means for distorting said current waves so as to develop harmonics, circuits for selecting said harmonics, and means individual to each selective circuit for reapplying said harmonics to said distorting means. 10
11. A source of current waves, means for distorting said current waves so as to develop harmonics, circuits for selecting said harmonics, and means for reapplying said harmonics to said distorting means and for adjusting the phase of any of said harmonics. 15
12. Means for producing current, means for distorting said current to produce harmonics, means for selecting said harmonics, and means for passing said harmonics through said distorting means in controllable amount. 20
- 25 13. A harmonic producer comprising an amplifier, means for overloading said amplifier to produce current distortion, selective circuits for receiving the distorted current, and individual connections for reapplying 30 components of different characteristics of said distorted current selectively to said amplifier.
- 35 14. A circuit into which harmonics are fed, means for separating said harmonics, a single amplifier for amplifying said harmonics, and individual connections for reapplying them in amplified form to said circuit.
- 40 15. A circuit having a plurality of means therein for selecting currents of different frequencies, load circuits associated with said respective means, and an amplifier having its output circuit associated with said first-mentioned circuit and its input circuit 45 associated with said load circuits.
- 45 16. A circuit having a plurality of means therein for selecting currents of different frequencies, load circuits associated with said respective means, an amplifier having its output circuit associated with said first-mentioned circuit and its input circuit associated with said load circuits, and means between said load circuits and said input circuit for independently shifting the phase 50 of said currents of different frequencies. 55
17. A harmonic producer comprising an amplifier having input and output circuits, a source of overloading current in its input circuit, means in its output circuit for separating harmonics, and connections between said means and said input circuit for causing any of said harmonics to be regenerated. 60
18. A harmonic generator and regenerator comprising a discharge device for producing harmonics, selective circuits for selecting said harmonics and means individual to said selective circuits for reapplying the harmonics to said discharge device. 65
19. A plurality of load circuits carrying currents of different frequencies, a plurality of circuits for supplying said currents, a common amplifier connected to the supply circuits for amplifying all said currents, and circuits connected to said amplifier for delivering the amplified currents selectively to 70 said load circuits.
20. A source of current, a plurality of load circuits in parallel relation fed from said source, an amplifier connected to said source and to said load circuits, and separate connections for supplying currents from said respective load circuits to said amplifier. 75
- 80 21. A harmonic producer comprising a source of base frequency current, a distorting and amplifying relay for said current for causing production of harmonics, and means for selecting desired harmonics and amplifying them by said relay. 85
22. In an amplifying system, an amplifying device having a control circuit and an output circuit, a first source of waves coupled to said control circuit, means for producing the harmonics of said first source of waves in said output circuit, selective devices for selecting said harmonics, and means for impressing the selected harmonics upon the control circuit. 90
- 95 23. In an amplifying system, an amplifying device having a control circuit and an output circuit, a first source of waves coupled to said control circuit, said amplifying device serving to cause harmonic currents in said output circuit, a selective device in said output circuit selective to said currents, and means to impress said selected currents upon the control circuit. 100
- 105 In witness whereof, I hereunto subscribe my name this 22nd day of September A. D. 1919.

RALPH V. L. HARTLEY.
